UNITED STATES PATENT OFFICE.

JAMES C. ANDERSON, OF HIGHLAND PARK, ILLINOIS.

MACHINE FOR DISINTEGRATING CLAY, CLAY-SHALE, &c.

SPECIFICATION forming part of Letters Patent No. 351,616, dated October 26, 1886.

Application filed August 5, 1886. Serial No. 210,105. (No model.)

To all whom it may concern:

Be it known that I, JAMES C. ANDERSON, a citizen of the United States, residing at Highland Park, in the county of Lake, State of Illinois, have invented certain new and useful Improvements in Machines for Disintegrating Clay, Clay-Shale, &c., of which the following is a specification, reference being had therein to the accompanying drawings.

10 My invention relates to improvements in machines for the reduction of clay, clay-shale, and analogous substances to a finely-divided condition.

15 My invention is designed as an improvement on the devices shown, described, and claimed in Letters Patent No. 271,588, granted to me February 6, 1883; and to this end my invention consists in mounting the rolls so that their peripheries will not impinge, and

20 in providing the surfaces of the eccentrically-mounted rolls, or rolls in which the surface of one is traveling faster than the other, with a series of cells or depressions for clutching or holding the clay, ore, or other material, while 25 it is being acted upon, so as to transfer the abrading or rubbing action from the rolls to the material itself, and in this way protect the surfaces of the rolls from rapid destruction.

Referring to the drawings, Figure 1 is a side 30 elevation of my improved machine. Fig. 2 is a top or plan view. Fig. 3 is a detached view of the reducing-rolls. Fig. 4 is a longitudinal sectional view of my machine, showing the screen and elevator for conveying the 35 coarse material back to the disintegrating-rolls. Fig. 5 is a detached view of a portion of the screen. Fig. 6 is a plan view of a portion of one of the reducing-rolls. Fig. 7 is a 40 sectional view of a portion of one of the reducing-rolls.

A indicate the reducing-rolls, which are mounted on their trunnions or bearings in a suitable frame, B, of any desirable construction, said rolls being provided with gear-wheels C C, of the same or of different size, so that the rolls can be driven at a uniform speed, or of different speeds, as may be desired.

One of the rolls A is provided with a gear-wheel, D, which meshes with and is driven by 45 a pinion-wheel, E, on the main driving-shaft F, said shaft F being driven by a belt which passes over the pulley G, and is connected to

any suitable source of power. One of the rolls A is mounted in movable bearings b, which are operated by set-screws e, so as to 55 regulate the distance between the rolls to suit the material to be operated upon.

The reducing-rolls A are elliptical in peripheral outline, and are arranged to rotate in opposite directions, as indicated by the arrows 60 in Fig. 3, such elliptical form being to compensate for the convergence incident to the changing or altering positions of the rolls when rotated in this direction. The trunnions or bearings of the rolls are eccentric to their axial 65 centers, so that a rapidly-changing peripheral speed is given to the rolls at the point of their nearest contact, and the material to be acted upon is subjected to a rubbing, abrading, and crushing action, which reduces or pulverizes 70 the same.

The periphery of a roll or other revolving body travels faster or has a greater velocity than the axis. Consequently when the clay or other material to be operated upon is caught 75 between the rolls it is subjected to the action of the periphery of the roll which is the greatest distance from the supporting-spindle, and as one surface of the roll is traveling faster than the other the material is subjected to a 80 rubbing, abrading, and crushing action, and will be thoroughly disintegrated.

The description of my invention thus far is essentially the same as embraced in the patent heretofore referred to, and the improvements 85 I have made thereto will now be described.

The rolls A are so mounted in their bearings and so timed in their revolutions that their peripheries will not touch at any time, and the peripheries of said rolls are provided with 90 cells or depressions d throughout their entire surface, for clutching and holding the clay, shale, or ore while it is being acted upon, so as to transfer the abrasion or rubbing action from the faces of the rolls to the contiguous 95 faces of the particles to be reduced, and in this way the surfaces of the rolls act simply as anvils, while the wearing-force or frictional contact is exerted between the particles of the material acted upon. The square or rectangular form of the cells d, which form I prefer to use, prevents the coarse particles of shale or ore from slipping and rubbing against the faces of the rolls.

H is a screen placed in an inclined position below the reducing-rolls, by which the coarser particles are separated from the finer. The coarse part, passing over the screen, finds a 5 lodgment in the compartment I, from whence they are taken by the elevator buckets and deposited in the chute L, which conducts it back into the hopper M, and thence back to the reducing-rolls. One of the rolls is provided with a yielding bearing, which may consist of a powerful spring placed next the journal-box, so as to hold the roll to the work, but will allow it to yield when undue strain is exerted on the same, and, as before intimated, 10 the rolls are so mounted that their surfaces do not impinge against each other when the machine is running empty, as is usually the case, and thus the surfaces are prevented from grinding together.

15 In operation, the material is first broken into small pieces of a comparatively uniform size in a separate breaking-machine, (not shown,) and deposited in the hopper M through the spout N, and is constantly fed from such breaking-machine to the hopper, so that the rolls are at all times provided with a sufficient quantity 20 of the material, the coarser portions which enter the hopper through the spout N coming in contact with the finer portions entering through the spout L and reducing the same 25 still further by frictional contact exerted by the cellular rolls.

30 In testimony whereof I affix my signature in presence of two witnesses.

I may obtain good results by mounting the rolls centrally to their respective axes and placing pulleys on the respective roll shafts in place of the gears, and rotating one of the rolls much faster than the other one, which will cause the material to rub together; but I prefer to use rolls in which the surface of one is

traveling faster than the other, said rolls being provided with cells, holds, or clutches for holding the material to be reduced in a vice-like grip so as to cause the material itself to be rubbed together, so as to reduce it to a powdered condition; and to carry out this method the eccentric rolls seem to be the best adapted to the purpose. It will be noticed, however, that these rolls, although of peripheral speed, must rotate together at the same axial speed, and when rotated toward each other, as they 45 must be, must be made slightly elliptical to conform at all times at the proper impinging points, and are therefore geared together conformably.

Having thus described my invention, what I claim, and desire to secure by Letters Patent, is—

1. In a machine for reducing clay, clay-shale, or other material, the reducing-rolls of which are provided with cells or depressions in their periphery, the surfaces of which are arranged to travel at variable or different speeds, as described, whereby the material is held by the cells and the material rubbed together, as set forth.

2. In a machine for disintegrating clay, clay-shale, and other material, the elliptical reducing-rolls A, mounted eccentrically, as described, the peripheries of which are provided with cells or depressions for holding the material while the contiguous particles are being reduced by frictional contact, as set forth.

In testimony whereof I affix my signature in presence of two witnesses.

J. C. ANDERSON.
